(57) **CLAIM**

The ornamental design for a tissue holder, as shown and described.

DESCRIPTION

FIG. 1 is a perspective view of a tissue holder showing my new design;

FIG. 2 is a top plan view thereof, the bottom view being a mirror image of the side shown;

FIG. 3 is a front elevational view thereof;

FIG. 4 is a first end view thereof;

FIG. 5 is a second end view thereof; and,

FIG. 6 is a rear view thereof.

The broken lines show portions of the design that form no part of the claimed design.

1 Claim, 2 Drawing Sheets
